UNITED STATES PATENT OFFICE.

WILLIAM J. CUNNINGHAM, OF TOLEDO, OHIO, ASSIGNOR OF ONE-HALF TO FRED G. MEYER, OF DETROIT, MICHIGAN.

SPARK-INTENSIFIER.

1,278,441.

Specification of Letters Patent. Patented Sept. 10, 1918.

Application filed May 28, 1917. Serial No. 171,515.

To all whom it may concern:

Be it known that I, WILLIAM J. CUNNINGHAM, a citizen of the United States, and a resident of Toledo, in the county of Lucas and State of Ohio, have invented a certain new and useful Spark-Intensifier; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to spark intensifiers and to one particularly adapted for use in connection with spark-plugs.

The primary object of my invention is the provision of an improved device of this character which is simple and inexpensive in its construction, capable of having the parts easily and quickly assembled, is less liable to breakage than similar devices heretofore used, and is adapted to be easily and quickly applied to a spark-plug. Other objects and advantages of the invention will be apparent to persons skilled in the art.

The invention is fully described in the following specification, and while, in its broader aspect, it is capable of embodiment in numerous forms, a preferred embodiment thereof is illustrated in the accompanying drawings, in which,—

Figure 1 is a side view of a device embodying the invention. Fig. 2 is an enlarged central longitudinal section thereof. Fig. 3 is a perspective view of the barrel member of the device, and Fig. 4 is a section of an electrode and its carrying member before attaching to the barrel.

Referring to the drawings, 1, 1 designate axially spaced electrodes, one of which projects inward from an end member 2, while the other projects inward from an end member 3. The end member 2, has a binding screw 4 threaded axially in its outer end for binding a terminal wire thereto, while the member 3 has an extension at its outer end provided with a transverse opening 5 for receiving the terminal post of a spark-plug to which it is attached.

A barrel 6, preferably of glass, coacts with the end members 2 and 3 to rigidly space the

same, and incloses the electrodes 1, 1. This barrel is provided adjacent to each end with 55 an external annular recess 7 for receiving the edge of an inwardly rolled annular flange 8 on the respective end member, whereby the barrel and end members are firmly secured together. The flange 8 of 60 each end member, before being attached to a barrel, is in the form of a cap, as shown in Fig. 4, for fitting over an end of the barrel, the edge of the flange being then turned into the recess 7 to hold the barrel. In order 65 to prevent a relative turning of the barrel and end members, each end member is provided on its outer edge with one or more lugs 9, which enter registering notches 10 in the barrel end.

It is evident that in assembling the barrel and end members, each end member is placed in end abutting relation to the barrel with its lugs 9 inserted in the registering notches 10, and with its flange 8 in open or outward 70 turned position. The flange edge is then subjected to an inward rolling or turning pressure by machine or otherwise, which causes its edge to enter the recess 7 in the adjacent barrel end and to coöperate therewith to firmly unite the two parts. When the device parts are assembled, the electrodes 1, 1 are held in rigid predetermined spaced relation, it being preferable to rigidly space the electrodes than to have them adjustable, 75 for if adjustable, a person using the same, unless experienced in such use, is apt to so adjust the electrodes that the gap is either too narrow or too wide. If the gap is too wide, injury is very apt to be done to the 80 electric generating means as is apparent to persons skilled in the art.

I wish it understood that my invention is not limited to any specific construction, arrangement or form of the parts as it is capable of numerous modifications without departing from the spirit of the claim.

Having thus described my invention, what I claim is new and desire to secure by Letters Patent is:—

A spark intensifier, comprising a sight barrel of transparent material having an axial opening therethrough and an external annular recess adjacent to each end and provided in the outer side of each end with 105 out the recess with a notch, an end member

for each end of the barrel fitting against the same and having an integral flange which extends around the barrel end and into the adjacent recess, said flange being provided with an integral lug for fitting into the adjacent end notch, each of said members also having an integral stud pro-

jecting into the respective end of the barrel and forming an electrode which is axially spaced with relation to the electrode of the other end member.

In testimony whereof, I have hereunto signed my name to this specification.

WILLIAM J. CUNNINGHAM.
